[57] CLAIM

The ornamental design for a golf putter head, substantially as shown.

DESCRIPTION

FIG. 1 is a perspective view of a golf putter head showing my new design;
FIG. 2 is an elevational side view thereof;
FIG. 3 is an elevational view of the side opposite to that shown in FIG. 2 thereof;
FIG. 4 is a rear elevational view thereof;
FIG. 5 is a front elevational view thereof;
FIG. 6 is a top plan view thereof; and,
FIG. 7 is a bottom plan view thereof.
